SHORT SUSPENDER

Charles H. Fowler, 750 High St. SE, Salem, Oreg.
Filed Sept. 4, 1962, Ser. No. 221,088
2 Claims. (Cl. 2—325)

The present invention relates to short suspender and has for an object a support for trousers having direct connection to the shirt whereby the shirt supports the load.

Another object of the invention is to dispense with the great length of conventional suspenders, with the six-point attachment thereof to trousers, with the front and rear attachment thereof to the trousers, with the application of the suspenders to the shoulders of the wearer, with the sliding action on the shoulders, and with other problems and annoyances incident to the use of suspenders as now constructed including the difficulty of drawing on the trousers with attached suspenders.

A further object of the invention is to provide short independent suspender straps applicable to side portions of the shirt beneath the armholes out of the way of arm and body action, leaving the shoulders free, and attachable to the trousers after same have been put on.

With the foregoing and other objects in view, the invention will be more fully described hereinafter, and will be more particularly pointed out in the claims appended hereto.

In the drawings, wherein like symbols refer to like or corresponding parts throughout the several views:

FIGURE 1 is a fragmentary front elevational view of the person of the wearer of a short suspender pursuant to the invention, illustrating one form of attachment between the shirt and trousers;

FIGURE 2 is a front elevational view of a form of short suspender having a series of buttonholes therein;

FIGURE 3 is a side elevational view of a shirt showing a button beneath the armhole thereof with which the buttonholes on the upper portion of the short suspender may be selectively engaged;

FIGURE 4 is a view taken on a magnified scale, similar to FIGURE 3, showing a short suspender attached to a button of the shirt and clipped to the trousers;

FIGURE 5 is a longitudinal sectional view taken on line 5—5 of FIGURE 4; and

FIGURE 6 shows a front elevational view of a modified form of the invention.

Referring more particularly to the drawings and for the present to FIGURES 1 to 5 inclusive, 10 designates a pair of trousers to be supported and 11 represents an outer shirt employed, according to the invention, as a basic support for the trousers.

Buttons 12 are sewed beneath armhole areas to the outer shirt 11 at the double seams thereof and are adapted to selectively receive buttonholes 15 of series of spaced buttonholes in the upper end portions of short suspender straps 13 arranged at the sides of the shirt and trousers and being of a length to extend between the waistband of the trousers and the lower portions of the shirt sleeves.

The lower ends of the straps 13 carry clips or clasps 14 which may be of a conventional or other type for detachable engagement with the upper edges of the trousers 10.

Referring to FIGURE 6, lower ends of the straps 13^a are slidably inserted through slots 17 of clip holders 13 and affixed at their terminals to the intermediate cross-bars 20 of adjusting clamps 19 through which slide the straps 13^a. In this case single buttonholes 15^a near the upper ends of the straps will suffice inasmuch as different effective lengths of the straps may be had either by the use of selective buttonholes of the series 15 or by the use of the clamps 19.

2

In the use of the invention, the straps 13 may be two in number independent of both shirt and trousers and sold separately. They are easily attached to the shirt by a buttoning operation, before or after donning the shirt, and to the trousers by opening the clips 14, setting the same to the waistband of the trousers and then closing the clips, after which the straps are beneath the arms of the wearer, out of the way, giving complete freedom of movement of the arms without stressing the straps.

10 The height of the trousers may be adjusted by adjusting the lengths of the straps in either manner as above described.

The invention involves no variation to conventional constructions of shirts and trousers and is compatible with 15 changing fashions in either or both.

Where the strap has several buttonholes, after adjustment to the desired buttonhole, the remainder of the strap above the selected buttonhole could be cut off, giving the desired length of strap without accumulations of 20 strap beneath the arms.

If desired the strap could be placed inside or outside the shirt and detached from or attached to the shirt, in which latter case the straps would act as reinforcements for the shirt.

25 The double seam on the shirt under the arm gives good support for the strap.

The strap may be like a suspender strap, either of elastic or inelastic webbing or other material.

It will be appreciated that while buttons and buttonholes are disclosed any other forms of complementary 30 fasteners may be used such as snap fasteners, one member of which is affixed to the shirt and the other member to the strap. In like manner, clips or clasps 14 have been disclosed as exemplary of fastening means by which the straps may be affixed to the trousers.

35 Although I have disclosed herein the best form of the invention known to me at this time, I reserve the right to all such modifications and changes as may come within the scope of the following claims.

40 I claim:

1. In combination
(a) a man's conventional outer shirt having double seams beneath armholes thereof,
(b) buttons secured over the double seams immediately beneath the armholes of the outer shirt,
(c) a pair of conventional outer men's trousers having a front opening,
(d) short straight elastic suspender straps, in number two only, initially detached from both the outer shirt and trousers and having
(e) a series of buttonholes in upper portions of the straps which, when selectively engaged with respective buttons, require the two short straight straps to depend from beneath armhole areas straight down along the double seams at the sides only of the shirt in positions with their lower end portions at the sides only of the trousers, and
(f) two-part fasteners depending freely at lower ends of the straps initially free of the trousers and in positions to overlap and detachably close upon inner and outer parts of the waistband of the trousers at side portions only of the trousers,
(g) so that the two straps while hanging each in a single straight vertical line will occupy zones of the person of the wearer only and solely beneath arm pits and completely only within the arms while hanging down loosely, leaving the arms freedom of movement in all directions without interference from the two short suspender straps.

2. In combination with a man's conventional outer shirt having double seams beneath armholes thereof and a pair of conventional outer trousers, short suspenders

for wholly supporting the trousers from the shirt in which the trousers, initially free of the suspenders, may be drawn on to the person of the wearer, consisting of

- (a) buttons secured over the double seams immediately beneath the armholes of the outer shirt,
- (b) short straight suspender straps of elastic material, in number two only, initially detached from both outer shirt and trousers,
- (c) said straps having in upper portions thereof a series of button holes which, when selectively fastened to the buttons, require the two short straight straps to depend from beneath the armhole areas straight down along the seams at the sides only of the shirt in positions with their lower ends free at the sides only of the trousers,
- (d) two-part fasteners depending freely at lower ends of the straps in positions to overlap and detachably close upon inner and outer parts of the waistband of the trousers at side portions only of the trousers,
- (e) so that the two straps while hanging each in a single straight vertical line will occupy zones of the

10

20

person of the wearer only and solely beneath arm-pits and completely only within the arms while hanging down loosely, leaving the arms freedom of movement in all directions without interference from the short suspenders, and

- (f) each strap being of a length to extend between the waistband of the trousers and the lower portions of the shirt sleeves.
